(57) **CLAIM**

The ornamental design for a wood stove, substantially as shown and described.

DESCRIPTION

FIG. 1 is a front perspective view of wood stove, showing my new design;

FIG. 2 is a perspective view thereof, with the stand retracted;

FIG. 3 is a front view of the wood stove of FIG. 1;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The evenly spaced broken lines depict portions of the wood stove that form no part of the claimed design. The dot dash dot broken lines denote the boundaries of the claim and form no part thereof.

1 Claim, 8 Drawing Sheets
